UNITED STATES PATENT OFFICE.

FREDRICK A. BAKER, OF BROOKLYN, NEW YORK.

FIRE-ESCAPE LADDER.

SPECIFICATION forming part of Letters Patent No. 280,459, dated July 27, 1880.

Application filed March 2, 1880. (Model.)

To all whom it may concern:

Be it known that I, FREDRICK A. BAKER, of Brooklyn, in the county of Kings and State of New York, have invented a new and useful 5 Improvement in Fire-Escape Ladders, of which the following is a specification.

The object of my invention is to provide ladders for the use of firemen which can be readily secured to the windows of buildings from 10 story to story to form a fire-escape.

The construction and operation will be more particularly described hereinafter with reference to the accompanying drawings, wherein—

Figure 1 is a perspective view of the ladder, 15 and Fig. 2 is a top view of one ladder-hook.

Similar letters of reference indicate corresponding parts.

A is the ladder, fitted at one end with hooks a a, which are adapted by their shape for taking hold upon a window-sill.

Upon each side of the ladder, near the upper end, is fitted a rigid arm, b, which arms, when the ladder is suspended from a window, will bear upon the wall of the building and retain 25 the ladder out from the wall free from obstructions. The ladder suspended in this manner is firmly held, and the top is level with the sill, so that it is easy to pass from the window to the ladder.

30 The hooks a are formed at their outer ends with pointed projections a', having beveled edges, as shown, so that they may enter between slats of blinds or act as wedges to break and split open blinds when the ladder is allowed to fall against the blind. The hooks a

also are provided with arms b', adapted to engage over and inside the window-sill.

Upon the upper end of the ladder is fitted a staple, c, for receiving a hook that carries a pulley, i, and rope, by which rope and pulley 40 a second ladder can be hoisted to the top of the first by persons on the ground, while a man at the top handles the ladder and hooks it to the window above. This may be readily done by the operator first strapping himself to the 45 lower ladder and using both hands to guide the second one as it is raised, and by these means the ladders are carried from story to story as high as required. There is also attached to the upper round of ladder A a rope, d, which is for 50 use for holding timid persons or for lowering goods.

A set of ladders constructed as described forms a useful and convenient apparatus for use at fires. The ladder for each story being 55 short and light, they may be readily handled and put in place, and long unwieldy ladders dispensed with.

Having thus described my invention, I claim as new and desire to secure by Letters Pat- 60 ent—

In a fire-escape ladder, the arm a, with the beveled projections a' and parts b', to engage over and inside the window-sill, in combination with the arms b, all constructed and ar- 65 ranged substantially as shown and described.

FREDRICK A. BAKER.
